SPEED LIMITING DEVICE

Homer M. Schubert, Salem, Oreg.

Application February 25, 1938, Serial No. 192,659

2 Claims. (Cl. 137—139)

This invention relates to speed limiting devices and is particularly adapted for automobiles, trucks, busses and so forth.

The primary object of the invention is to limit the fuel supply to the motor vehicle when said vehicle has reached a predetermined speed over the ground surface.

In my invention I do not alter any of the present mechanism, but I do add an auxiliary butterfly or throttle valve between the carburetor and manifold of the motor. This valve is controlled preferably by an electric magnet, said magnet being energized by an electric contact which is completed when the speed of the vehicle reaches a certain predetermined speed. Means are provided for adjusting this predetermined speed within the speedometer or other suitable governing device which would close an electric contact at a predetermined speed.

Another object of my invention is to provide means for adjusting my auxiliary throttle valve at a predetermined time.

These and other incidental objects will be apparent in the drawing, specification and claims to follow.

Referring to the drawing:

Figure 1 is a perspective side view of my invention consisting of an auxiliary throttle controlled by an electric magnet, the same being removed from the carburetor and manifold.

Figure 2 is a fragmentary side view of a manifold and a carburetor having my auxiliary control speed limiting device installed therebetween.

Figure 3 is a diagrammatical view of a speedometer or other suitable speed indicator employed in connection with any invention.

In the drawing:

1 is the manifold of the motor vehicle having my auxiliary control throttle assembly 2 mounted between the manifold and the carburetor 3. The main body of the auxiliary control throttle is shown at 4, having a housing 5 integral therewith. The auxiliary valve is shown at 6 mounted to the shaft 7. An electric solenoid 8 is fixedly mounted within the housing 2 having a movable core 9. The core 9 works within the solenoid 8 and is connected to the arm 10 by the connecting link 11. The arm 10 is fixedly mounted to the shaft 7 and revolves the auxiliary valve 6 within the main housing 4. A spring 12, having one end secured to the housing at 13, and its opposite end to the core 9 at 14, normally holds the valve 6 in open position. The amount of closing of the valve 6 may be governed by the adjusting

screw 15 and this adjusting screw may be sealed by a seal 16.

The adjustment of this screw limits the travel of the end of the dash-pot and core 9 to a predetermined amount preventing the throttle 6 from closing entirely but only to this predetermined amount, which coincides very closely to the speed that the vehicle is governed to run. The reason for adjusting the throttle in this way is to prevent entire closing of the fuel stream causing the vehicle to operate more smoothly, the throttle 6 being wide open until the car reaches the predetermined governed speed. Then when the solenoid 8 is energized by the electric contact within the governor mechanism, the throttle will only be closed sufficient to prevent over-running the governed speed.

Referring to Figure 2, an adjustable electric contact 17 is provided within the speed indicator or governor. When the contact arm 18 reaches the contact 17 electric energy will be supplied to the solenoid 8 by the conductor 19, terminals 20, 21 and conductor 22 to the source of electric energy, as the battery 23. The closing of this contact, within the speed indicator 30 and the energizing of the solenoid 8 pulls the core 9 to the right manipulating the arm 10 and revolving the shaft 7 and closing the auxiliary valve 6 till the speed has been reduced sufficient to allow the contact arm 18 to disengage itself from the contact 17 demagnetizing the solenoid 8. The spring 12 will then open the valve 6 by pulling the core 9 to the left. During this auxiliary control action, the main throttle valve 24 need not be manipulated as it will come into play or action as the valve 6 has been opened again. In order to prevent too rapid a closing or opening of the valve 6 a dash pot cylinder 25 may be employed having a piston 26 working therein and connected to the core 9 by the piston rod 27. Sufficient air may pass through the bearing 28 or the opening 29 to allow proper action of the dash pot controlling the speed of the core 9 in either direction.

It will be apparent from the above description that the setting of the contact 17 within the speed indicator 30 at any of the points 31 will determine the speed at which the auxiliary valve 6 will be manipulated or closed by the solenoid 8. The whole assembly within the housing 2 is closed and sealed by a cap or face plate 32.

I do not wish to be limited to the particular form of embodiment herein shown, as my invention is adapted to other mechanical combina-

tions, still coming within the scope of the claims to follow.

What is claimed to be new is:

1. A speed limiting control for motor vehicles and the like, including a gas control valve arranged intermediate the normal throttle valve and intake manifold of the engine for controlling the passage of gas to the intake manifold, an electric coil supported adjacent the valve, a core within and operated by the coil, a connection between the core and valve to operate the valve toward closed position in the movement of the core responsive to the energization of the coil, a dash-pot aligned with the coil and including a piston connected to the core, and a screw rod mounted for threaded movement relative to and serving to limit the movement of the piston.
2. A speed limiting control for motor vehicles

and the like, including a gas control valve arranged intermediate the normal throttle valve and intake manifold of the engine for controlling the passage of gas to the intake manifold, an electric coil supported adjacent the valve, a core within and operated by the coil, a connection between the core and valve to operate the valve toward closed position in the movement of the core responsive to the energization of the coil, a dash-pot aligned with the coil and including a piston connected to the core, a screw rod mounted for threaded movement relative to and serving to limit the movement of the piston, and a spring connected to a fixed part of the structure and to the core to move the core in opposition to its movement on energization of the coil. 10 15
